UNITED STATES PATENT OFFICE.

GRAYSTON L. OHMART, OF DETROIT, MICHIGAN.

GARAGE-DOOR HOLDER.

Application filed March 20, 1924. Serial No. 700,683.

To all whom it may concern:

Be it known that I, GRAYSTON L. OHMART, a citizen of the United States, residing at Detroit, in the county of Wayne and State 5 of Michigan, have invented certain new and useful Improvements in a Garage-Door Holder, of which the following is a specification.

The present invention relates to a garage 10 door holder and has for its principal object to provide simple and efficient means for holding a garage door of the swinging type in an open position while an automobile is being backed into the garage. Considerable damage has been caused to automobiles 15 while running them into garages because of the wind closing the door and colliding with the automobile. The present invention eliminates this danger.

Another important object of the invention 20 is to provide a device of this nature which may be manufactured at a comparatively low cost, easily installed, reliable in operation, and well adapted to the purpose for 25 which it is designed.

With the above and numerous other objects in view as will appear as the description progresses, the invention resides 30 in certain novel features of construction, and in the combination and arrangement of parts as will be hereinafter more fully described and claimed.

In the drawing—

Figure 1 is a fragmentary rear elevation 35 of a door and frame therefor showing my invention applied thereto.

Figure 2 is a top plan thereof showing the door in an open position, and

Figure 3 is a detail section through the 40 catch.

Referring to the drawing in detail it will be seen that 1 designates a door frame to which is hinged the door 2 as at 3. My device consists of a pair of rods 4 and 5. The rod 4 is pivoted at one end to the upper 45 portion of the frame 1 as at 6 and at its other end to one end of the rod 5. The other end of the rod 5 is pivoted to an intermediate portion of the door 2 as at 7. It 50 is to be noted that the rod 5 is bent intermediate its ends so as to provide two diverging portions so that when the door is in an open position as shown in Figure 2 one portion thereof will extend parallel 55 with the door and the other portion angularly therefrom. A catch indicated generally

at 8 is mounted on the door and adapted to engage the portion of the rod 5 which is adjacent the pivot point 7. This catch 8 includes a U-shaped body portion 9 including an upper leg 10 and a lower leg 11 both of which are apertured as at 12 and 13. A plate 14 provided with an aperture is fixed to the body 9 intermediate its ends and adjacent the upper leg 10. A bolt 17 60 is projected through the aperture 13 of leg 11 and the aperture of the plate 14 terminating above the plate 14 in a beveled surface. A pin 18 is mounted through the bolt 17 adjacent the plate 14 and a spring 70 19 is disposed about the bolt 17 and normally holds the beveled face of the bolt projected through the aperture of plate 14. A chain 20 is connected to the bottom end of the bolt 17 so that the same may be pulled 75 downwardly thereby compressing the spring which will return the bolt after the chain is released. The portion of the rod 5 adjacent pivot 7 moves between the leg 10 and plate 14 and in so moving will depress the 80 bolt 17 and move beyond the aperture 12 and allow the bolt to spring back in position thereby locking this rod and preventing movement of the door 2 as will be clearly understood. 85

I have, in the present instance, shown and described the preferred embodiment and use of my invention which will give in practice satisfactory and reliable results, and it is to be understood that the same 90 is susceptible of modification in various particulars without departing from the spirit or scope of the invention or sacrificing any of its advantages.

Having thus described my invention what 95 is claimed as new is:—

1. In combination, a door frame, a door hinged to the frame, a rod pivoted to the frame, a second rod pivoted to the door, said second rod being bent intermediate its 100 ends to provide two straight portions diverging from each other, said rods being pivoted to each other, and a catch on the door for engaging the second rod in the manner and for the purpose specified. 105

2. In combination, a frame, a door hinged to the frame, and means for holding the door in an open position, said means including a pair of rods pivoted to each other, one of said rods pivoted to the frame, the other rod being pivoted to the door and formed in two sections angularly disposed 110

in relation to each other, the section adjacent the door adapted to lie parallel therewith when the door is in an open position, and a catch on the door for engaging said last mentioned section of the rod.

3. In combination, a frame, a door hinged to the frame, and means for holding the door in an open position, said means including a pair of rods pivoted to each other, one of said rods pivoted to the frame, the other rod being pivoted to the door and

formed in two sections angularly disposed in relation to each other, the section adjacent the door adapted to lie parallel therewith when the door is in an open position, and a catch on the door for engaging said last mentioned section of the rod, said catch including a body and a spring bolt, means for actuating the spring bolt so as to release the section of the rod engaged thereby. 15

In testimony whereof I affix my signature.

GRAYSTON L. OHMART. 20
